UNITED STATES PATENT OFFICE

CARL BAUER, OF CHICAGO, ILLINOIS, ASSIGNOR TO DOETSCH & BAUER COMPANY, OF CHICAGO, ILLINOIS, A CORPORATION OF ILLINOIS

DESIGN FOR A SETTEE FRAME OR SIMILAR ARTICLE

Application filed April 8, 1929. Serial No. 30,793. Term of patent 3½ years.

To all whom it may concern:

Be it known that I, CARL BAUER, a citizen of the United States, residing at Chicago, in the county of Cook and State of Illinois, have invented a new, original, and ornamental Design for a Settee Frame or Similar Article, of which the following is a specification, reference being had to the accompanying drawing, forming a part thereof.

Fig. 1 is a perspective view of a settee frame or similar article showing my new design and Fig. 2 is an enlarged detail of a portion of the carving on the settee frame.

I claim:

The ornamental design for a settee frame or similar article as shown.

In witness whereof, I hereunto subscribe my name this 27th day of March, 1929.

CARL BAUER.
